UNITED STATES PATENT OFFICE

KARL NOLTE, OF HANOVER, GERMANY

SHEET PILING OF BOX SHAPE

Application filed January 6, 1928, Serial No. 244,929, and in Germany April 6, 1927.

Iron sheet pilings have been proposed for developing large resistances, wherein the individual box-shapes are connected, either at the neutral axis, or at the outer line. With 5 connections at the neutral axis the moment of resistance to rotational stress is small with the known connections, because the individual box-shapes are connected to each other more or less movably by special connecting members.

According to the present invention this disadvantage is got rid of by locating the connections towards the inside and by making the individual boxes touch each other by 15 their front faces; also by providing locking bars for the purpose of holding the boxes together.

The Figs. 1 and 2 of the accompanying drawings show a construction of the piling according to the invention in cross section. Two U-shaped iron sections *a* and *b*, the ends *c* and *d* of which are bent inwards at right angles, are placed with the open sides opposite each other. Then the locking bar *e* which 20 corresponds with the bent ends *c* and *d*, is driven in, whereby the box is held together. In order to prevent a shifting of the locking-bar *e*, it may be made wedge-shaped or be provided with a lug *f*, which lies against the 25 surface of *a* and *b*. The individual construction of the connections can naturally be of the most various shapes.

Having now particularly described and ascertained the nature of my said invention and in what manner the same is to be performed, I declare that what I claim is:—

1. Iron sheet box-piling of the kind referred to, comprising hollow members provided with neutral axis connections located 40 within the members, the latter being in addition so shaped that their adjacent faces abut against one another.

2. Iron sheet box-piling of the kind referred to, comprising hollow members each 45 having centrally disposed along a face an

opening the edges of which are turned inwards for engagement by a T-shaped connection.

3. Iron sheet box-piling of the kind referred to, comprising hollow members each 50 consisting of two channel shaped members having inturned edges, and locking bars which are of T-shape in cross section and which engage the inturned edges to lock the hollow members in abutting relation.

4. Iron sheet box-piling of the kind referred to, comprising hollow members each 55 consisting of two channel shaped members having inturned edges, and locking bars which are of double T-shape in cross section 60 for engaging the inturned edges.

5. Iron sheet box-piling of the kind referred to, comprising hollow members each 65 consisting of two channel shaped members the side faces of which are at right angles to the body portion thereof and the edges turned inwards.

6. Iron sheet box-piling of the kind referred to, comprising hollow members each 70 consisting of two channel shaped members the side faces of which are at right angles to the body portion thereof and the edges turned inwards, and locking bars which are of double T-shape in cross section for engaging the inturned edges.

7. Iron sheet box-piling of the kind referred to, comprising hollow members each 75 consisting of two channel shaped members the side faces of which are at right angles to the body portion thereof and the edges turned inwards, and locking bars which in cross section are of double anchor shape for engaging the inturned edges.

8. Box piling comprising pairs of symmetrically arranged channel shaped sections, the 80 members of each pair being arranged with their channels adjacent, and means between the sections of adjacent pairs for locking the sections together and for locking adjacent pairs in face to face abutting relation.

9. Box piling comprising pairs of symmetrically arranged similar substantially channel shaped sections having inturned side edges, and locking bars extending between the side edges of the members of adjacent pairs and having means to engage the inturned edges, thereby to lock the pairs together.

In testimony whereof I have affixed my signature.

KARL NOLTE.
